(57) **CLAIM**

The ornamental design for an upper handle for photography device, as shown and described.

DESCRIPTION

FIG. 1 is a front view of an upper handle for connecting to a photography device according to the present design; FIG. 2 is a rear view of the upper handle for photography device of FIG. 1;

FIG. 3 is a top view thereof;

FIG. 4 is a bottom view thereof;

FIG. 5 is a right side view thereof;

FIG. 6 is a left side view thereof; and,

FIG. 7 is a perspective view of the upper handle for photography device of FIG. 1.

The broken lines shown represent portions of the upper handle for photography device that form no part of the claimed design.
